UNITED STATES PATENT OFFICE.

JACOB S. BENDER, OF KANSAS CITY, MISSOURI.

GRAIN-DOOR FOR BOX-CARS.

No. 880,476.

Specification of Letters Patent.

Patented Feb. 25, 1908.

Application filed December 8, 1906. Serial No. 346,862.

To all whom it may concern:

Be it known that I, JACOB S. BENDER, a citizen of the United States, residing at 1857 Jefferson street, Kansas City, in the 5 county of Jackson and State of Missouri, have invented certain new and useful Improvements in Grain-Doors for Box-Cars, of which the following is a specification.

My invention relates to improvements in 10 grain doors for box cars, and my object is to produce a door of this character which will prevent leakage of grain, will successfully resist the pressure of the grain, and may be easily opened regardless of said pressure.

15 The door embraces two sections, the upper one of which is slidably and pivotally mounted, while the lower one is hinged, so that it may be let down preparatory to unloading the car.

20 In order that the invention may be fully understood, reference will now be made to the accompanying drawings, in which—

Figure 1 shows a broken interior view of a 25 box car provided with my improved grain door. Fig. 2 is a broken exterior view of the same. Fig. 3 is a broken cross section on line III—III of Fig. 1. Fig. 4 is a broken horizontal section on line IV—IV of Fig. 1. Fig. 5 is a broken horizontal section on line 30 V—V of Fig. 1. Figs. 6 and 7 represent a pair of castings forming part of the invention.

In carrying out the invention I provide a 35 door consisting of an upper section 1 and a lower section 2. Section 1 is strengthened by transverse corrugations 3, so that it may be made of thin metal in order to reduce its weight as much as possible, and yet give it the requisite strength to successfully resist 40 the strain imposed thereon by the grain. It is provided at its ends with vertical flanges 4, which snugly fit against the inner sides of the door posts 5, and thus prevent leakage of grain at these points. Said upper section is also provided with a pair of 45 sheaths 6 for the reception of a pair of slotted links 7, upon which the upper section is suspended, it being normally supported at the lower ends of the links by bolts 8 extending through the sheaths, the slots of the 50 links and the section.

The upper ends of links 7 pivotally engage a pair of eye-bolts 9, while their lower ends are formed into inturned hooks 10, which 55 slide within and engage the lower ends of the sheaths when section 1 is slid upwardly

on the links preparatory to raising it to the position shown by dotted lines, Fig. 3, where it is supported by hooks 10^a pivotally secured to the carlines 11.

60 By first sliding sections 1 upwardly it is obvious that their adjacent ends will not overlap when swung to the position shown by dotted lines, Fig. 3. Hence they may be easily engaged with or disengaged from 65 said hooks and either one may be let down without disturbing the other.

When in a lowered position the upper section overlaps the lower section 2 against which it abuts its entire width to prevent 70 leakage of grain between the two sections. Section 2 is reinforced with a pair of inwardly turned end flanges 12 and an outwardly turned longitudinal flange 13 along its upper edge. It is further reinforced 75 with a longitudinal strap 14, which unites hinge members 15, integral with the lower portion of section 2. Hinge members 15 are secured to similar members 16, integral with a threshold plate 17, by a pintle 18.

80 19 designates a pair of castings secured to the floor of the car and the lower ends of posts 5, and provided with inclined pockets 20, to receive flanges 12, and thus prevent leakage of grain at the ends of the lower section. Said 85 castings are also provided with reversely-disposed keepers 21 22 for the reception of the ends of a bar 23 employed to reinforce and lock the lower section in a closed condition, see Figs. 2 and 3.

90 Bar 23 is pivotally secured by a bolt 24 to the upper central portion of section 2, so that when the latter is closed, said bar may be swung to the position shown in Fig. 2, and thus engage behind the keepers, grooves 25 95 being provided at the rear thereof for the reception of the terminals of the bar.

100 The swinging movement of bar 24 is limited by a pair of loops 26 on member 2, and when in engagement with the keepers its movement is further limited by a latch 27, so that its ends cannot disengage the keepers until said latch is swung to an inoperative position. Latch 27 is pivoted to section 2 by a pin 28 adjacent to one of the loops, so that the latter 105 will support the latch in its operative position, when it is swung into engagement with said loop. See Fig. 2.

110 Both sections set in from the path of the outside door A, with which box cars are usually equipped, and the lower section is so hinged that when opened it will swing down

to a perpendicular position and be out of the way of the outside door. Thus when the car is loaded with merchandise, which does not require a tightly fitting door, my sections 5 may be swung to their inoperative positions, so that only the outside door A will have to be opened when it is desired to gain access to the interior of the car.

Section 2 is made considerably shorter per- 10 pendicularly than section 1, so that when the car is loaded with grain the bulk of the weight against the door will be upon the upper section. Hence the lower section may be readily opened when it is desired to unload the 15 car, so that sufficient grain may be taken from the opening thus left to allow the upper section to be swung upwardly out of the way and give access to the interior of the car, preparatory to unloading the remainder of the 20 grain.

Having thus described my invention, what I claim is:

1. A grain door for cars having a hinged section, loops secured to said section, a bar 25 pivoted to the section for locking the same, the ends of said bar extending through the loops, keepers adapted to be engaged by said ends and a latch pivoted to the section adapted to be turned into one of the loops beneath 30 and hold the bar in a locked position.

2. A grain door for cars consisting of an upper section, a hinged lower section provided at its upper ends with inturned flanges, castings secured to the door posts of the car and 35 provided with pockets for the reception of the flanges and with reversely disposed keepers, and a locking bar pivoted to the outer face of said lower section with its ends adapted to engage behind said keepers.

40 3. A grain door for cars consisting of an upper section, a lower section provided along its upper edge with an outturned reinforcing

flange and along its lower edge with hinge members, a threshold plate to which the hinge members are pivotally secured on a line outside the plane of the upper section, castings secured to the door posts of the car and provided with inclines and means for locking the lower section against said inclines.

4. A grain door for cars consisting of an 50 upper section, a lower section provided along its upper edge with an outturned reinforcing flange and along its lower edge with hinge members, a threshold plate to which the hinge members are pivotally secured on a line outside the plane of the upper section, inturned 55 flanges at the ends of said lower section, castings on the door posts provided with inclined pockets adapted to receive said flanges and with oppositely disposed keepers laterally beyond said pockets, and a locking bar centrally pivoted to the lower section with its extremities adapted to engage between said keepers when said flanges are in place.

5. A grain door consisting of a lower section, 65 an upper section provided with vertical sheaths, slotted links arranged in said sheath and provided with inturned hooks for engaging the lower ends thereof after the upper section has been slid upwardly, bolts passing 70 through the upper ends of the sheaths, the slots in the links, and the section, means above the doorway to which the links are pivotally secured so that they may swing upwardly with the upper section, and hooks 75 for supporting said upper section in a raised position.

In testimony whereof I affix my signature, in the presence of two witnesses.

JACOB S. BENDER.
